US00D668029S

(12) **United States Design Patent**
Vestuti et al.(10) **Patent No.:** US D668,029 S
(45) **Date of Patent:** ** Oct. 2, 2012(54) **PORTION OF A SHOE**(75) Inventors: **Ricardo Vestuti**, Providence, RI (US);
Daniel Hobson, Waltham, MA (US)(73) Assignee: **Reebok International Limited**, London
(GB)(**) Term: **14 Years**(21) Appl. No.: **29/418,772**(22) Filed: **Apr. 20, 2012****Related U.S. Application Data**

(60) Division of application No. 29/408,163, filed on Dec. 7, 2011, now Pat. No. Des. 659,959, which is a continuation of application No. 29/362,605, filed on May 27, 2010, now Pat. No. Des. 652,201.

(51) **LOC (9) Cl.** ..... **02-99**(52) **U.S. Cl.** ..... **D2/951**; D2/977; D2/946(58) **Field of Classification Search** D2/896,

(57) **CLAIM**

The ornamental design for a portion of a shoe, as shown and described.

DESCRIPTION

FIG. 1 is a top plan view of a shoe showing our new design; FIG. 2 is a bottom view thereof; and, FIG. 3 is a side view thereof.

The broken lines in the Figures show environment for illustrative purposes only and form no part of the claimed design. The area within the solid and dash-dot lines forms the claimed design.
